(57) **CLAIM**

The ornamental design for a athletic shoe, as shown and described.

DESCRIPTION

FIG. 1 is a perspective view of an athletic shoe showing my/our new design;

FIG. 2 is a back elevation view of the athletic shoe of FIG. 1;

FIG. 3 is a first side elevation view of the athletic shoe of FIGS. 1 and 2;

FIG. 4 is a second opposite side elevation view of the athletic shoe of FIGS. 1-3;

FIG. 5 is a top plan view of the athletic shoe of FIGS. 1-4; and,

FIG. 6 is a bottom plan view of the athletic shoe of FIGS. 1-5.

The broken lines illustrate portions of the athletic shoe that form no part of the claimed design.

1 Claim, 6 Drawing Sheets
